US00D906138S

(12) **United States Design Patent** (10) **Patent No.:** **US D906,138 S**
(45) **Date of Patent:** **** Dec. 29, 2020**

(54) **REMOTE SENSOR DEVICE**

(71) Applicant: **ECOBEE INC.**, Toronto (CA)

(72) Inventor: **Jonathan Hayes**, Cambridge, MA (US)

(73) Assignee: **ECOBEE INC.**, Toronto (CA)

(**) Term: **15 Years**

(21) Appl. No.: **29/675,346**

(22) Filed: **Dec. 31, 2018**

(51) **LOC (12) Cl.** **10-04**

(52) **U.S. Cl.**

USPC **D10/53; D10/70; D10/106.6**

(58) **Field of Classification Search**

USPC **D10/46, 52, 53, 70, 106.6**

CLAIM

The ornamental design for a remote sensor device, as shown and described.

DESCRIPTION

FIG. 1 is a perspective view of a remote sensor device showing a new design for a remote sensor device; FIG. 2 is a front plan view thereof; FIG. 3 is a rear plan view thereof; FIG. 4a is a top plan view thereof; FIG. 4b is a bottom plan view thereof; FIG. 5a is a side plan view thereof; and, FIG. 5b is another side plan view thereof. The broken lines shown in FIG. 3 illustrate portions of the remote sensor device that form no part of the claimed design.
